EXPANSIBLE WATCH BRACELET

Arthur Albanese, Providence, R. I., assignor to Marvel Jewelry Mfg. Company, Providence,
R. I., a corporation of Rhode Island

Application April 24, 1950, Serial No. 9,446

Term of patent 7 years

(Cl. D45—4)

To all whom it may concern:

Be it known that I, Arthur Albanese, a citizen of the United States, residing at Providence, in the county of Providence and State of Rhode Island, have invented a new, original, and ornamental Design for an Expansible Watch Bracelet, of which the following is a specification, reference being had to the accompanying drawing, forming part thereof, wherein:

Figure 1 is a top plan view of an expansible watch bracelet embodying my new design, the links shown in full lines being repeated throughout the length of the bracelet as indicated by the dot and dash lines, portions of some of the links being broken away for illustrative purposes only.

Fig. 3 is an enlarged top perspective view of one of the top links.

Fig. 4 is an enlarged perspective view illustrating the bottom of one of the top links.

I claim:

The ornamental design for an expansible watch bracelet, as shown and described.

ARTHUR ALBANESE.
